UNITED STATES PATENT OFFICE.

HENRY W. JACOBS, OF TOPEKA, KANSAS, AND EDWARD D. LEVY, OF SPRINGFIELD, MISSOURI.

CAR.

1,221,740.

specification of Letters Patent.

Patented Apr. 3, 1917.

Application filed November 1, 1915. Serial No. 59,126.

To all whom it may concern:

Be it known that we, HENRY W. JACOBS and EDWARD D. LEVY, citizens of the United States, and residents of Topeka, in the county of Shawnee and State of Kansas, and Springfield, in the county of Greene and State of Missouri, respectively, have invented certain new and useful Improvements in Cars, of which the following is a description, reference being had to the accompanying drawings, which form a part of our specification.

Our invention relates to house-cars of all steel construction, and more particularly refers to the underframe, floor, walls, and roof of the car; our improved construction being suitable for all classes of house-cars such as furniture, refrigerators, automobiles, express and box-cars; applying more especially to a box-car construction.

The object of our invention is to provide a house-car that will be simple in design, inexpensive to manufacture, light in construction and at the same time possess a great amount of strength.

A further object of our invention is to provide a car-construction embodying the least possible amount of framework; the walls of the car being composed of steel sections, which, in themselves, will provide the necessary rigidity for the walls and the roof. Our improved car-construction, furthermore, is also burglar proof and fire proof and offers the maximum amount of resistance to destruction in case of derailment.

The advantages of our improved construction will be readily apparent from the following detailed description of the accompanying drawings, wherein:

Figure 1 is a perspective view with portions removed to show the interior construction, while other parts are shown in cross-section in order to more clearly disclose the detailed construction.

Fig. 2 is a detailed cross-sectional view to more clearly disclose the construction of the roof.

Fig. 3 is a cross-sectional view through a portion of the car to more clearly disclose the wall construction thereof.

Fig. 4 is a modified form of our improved house-car, shown in perspective with parts removed while other parts are shown in cross-section.

Fig. 5 is a perspective view of one end of

our improved steel car-construction, with internal linings shown in partial cross-section; the construction of the car illustrated being provided with fittings so as to constitute a refrigerator car.

Fig. 6 is a longitudinal sectional view taken through the floor of the car shown in Fig. 5.

Fig. 7 is a plan or side elevation of a modified form of the end of a car employing our invention.

Fig. 8 is a detail view in side elevation of a part of the side wall of a modified form of our steel-construction, showing the insertion of wooden nailing strips.

Fig. 9 is an end elevation of the construction shown in Fig. 8.

Fig. 10 is a detail plan view showing a method which may be employed for securing blocking in place in the house-car by means of wire, rope, chain, &c.

Fig. 11 is a vertical sectional view taken through Fig. 10.

Fig. 12 is a detail plan view illustrating a modified form for securing blocking to the sides and floor of our improved all steel construction.

Fig. 13 is a cross-sectional view taken through the vertical axis of Fig. 12.

The particular exemplification of our invention, as illustrated in the first figure of the drawings, discloses the side walls of the car as consisting of the metallic sections or triangulated steel plates 15, with the narrow or truncated end of the succeeding plate 90 extending in an opposite direction, as can very clearly be seen to the right in Fig. 1. The floor of our improved all steel-car is also preferably formed of similar metallic sections 16, with the narrow or truncated ends of each alternate section extending in opposite direction, in a manner similar to that of the side wall sections. The floor-construction can be seen to the left in Fig. 1.

The side wall sections, as well as the floor sections, may be made of any suitable size, being preferably of similar size and shape so as to be interchangeable, thus providing a proper proportion to the car and keeping the number of parts of different styles down to a minimum.

The longitudinal sides of the side sections 15 are flanged, and the flanges 17 are disposed outwardly. The flanges of the adjacent sections are secured together by any

suitable means such as rivets, bolts or welding, but preferably by means of rivets.

The floor sections 16, like the side wall sections 15, also have their longitudinal sides flanged, as shown at 18 to the left in Fig. 1. The flanges of the floor-sections 16 are preferably disposed vertically on the upper side of the floor-sections in order that they may be easily secured together by means of rivets 19 or in any other suitable manner. If desired, of course, the flanges of the floor-sections may be extended downwardly, but for convenience in securing the respective sections together we prefer to arrange them in the manner disclosed in Fig. 1. By arranging or disposing the flanges of the floor-sections upwardly as disclosed in Fig. 1, the floor-sections 16 provide a flat under surface, enabling the floor-sections to be securely fastened to the underframe of the car by means of bolts or rivets. By presenting the cupped or dished side of the floor-sections upwardly, the floor-sections may be filled in with any suitable plastic fire proof material as, for example, shown at 19; the covering or filler 19 constituting the service floor of the car.

The end walls of our improved car, as illustrated in Fig. 1, are formed of rectangular metal plates 20, the edges whereof are flanged in a manner similar to that of the side sections, and preferably presented outwardly, as shown in Fig. 1 and more clearly in the sectional view in Fig. 3. In view of the additional strains to which the ends of the car are subjected, we prefer to provide the intervening structural steel T-sections 21, as shown to the right in Fig. 1 and more clearly in Fig. 3. The adjacent flanges and T-sections are preferably riveted together as indicated in 22 in Fig. 3. The side and end walls are secured together by means of corner posts preferably of Z-bar construction in cross-section. The Z-bars 23 are preferably riveted to the adjacent flanges of the side sections 15 and the end sections 20, as shown more clearly in Fig. 3. By employing the reinforcing members 21 and 23, greater strength is given to the ends of the car while at the same time a very simple and efficient construction is produced.

The end wall, which is an entire steel construction, is securely fastened by rivets or otherwise to the end sill 24, see Fig. 1; the latter being securely riveted or otherwise fastened to the draft sills 25 and the side sills 26, thereby providing a very rigid and strong construction.

As disclosed in Fig. 1 and to the left thereof, we prefer to build the body bolster 27 integral with the underframe of the car; the body bolster being preferably of the hollow column construction shown in Fig. 1. Suitable cross ties 28 and 29 are preferably employed to give the necessary strength desired. Angle braces 30, in the

nature of channel steel, are also preferably employed at the ends of the underframe, as shown to the left in Fig. 1. We prefer to provide the center sills and side sills with the side plates 31 in order to give necessary strength in the middle span of the underframe; the side plates 31 being shown reinforced by means of the angle iron 32, thereby insuring the greatest possible strength with the least possible weight.

We have shown our improved car provided with an all steel door 33, which is preferably adapted to be flush with the side walls of the car when in closed position. The door 33 is also shown provided with auxiliary doors at the top and bottom thereof, as shown at 34 and 35, respectively, for the purpose of loading and unloading such material as loose grain, charcoal, coke, &c. The construction shown and described greatly facilitates the matter of loading and unloading; and if the side door is made flush it is possible to make the same grain-tight and waterproof so that additional doors for this purpose are not required. The upper part of the walls is preferably provided with a top frame 36 of Z-bar construction, as can more clearly be seen to the right in the upper corner of Fig. 5.

The roof of our improved car is preferably composed of a series of flanged sheet metal sections 37, as very clearly shown in Figs. 1 and 5. The roof sections preferably have their flanged sides presented outwardly or upwardly, as shown in the drawings, and may be bent or bowed so as to provide the arched roof, as shown in the drawings. The ends of the roof-sections 37 are also preferably flanged so as to extend laterally or outwardly, thereby providing a portion which will extend parallel with the intermediate portion or leg of the Z-bar 36. The side sections 15 also have their upper ends preferably flanged outwardly so as to lie flush with the bottom side of the intermediate portion of the Z-bar 36, as can more clearly be seen in Fig. 2. By flanging the ends of the roof-sections, as well as the top edges of the side sections, we provide parallelly extending portions which may be secured together by a single row of rivets 38, see Fig. 2. Instead of riveting these respective sections together, it is evident that any suitable means may be employed for securing the end members together as, for example, bolts; it being evident, however, that the construction will not only be very rigid but will also be waterproof.

The roof-sections 37, which are also of steel, preferably have their vertical extending flanges secured together by means of rivets in order that water-tight joints may be provided; any suitable manner, however, of securing the flanges together may be employed.

5 The car is shown provided with the usual running board 39 made in accordance with the approved safety appliance rules; and the car is also provided with the usual side ladders 40, end ladders 41, and all other necessary safety appliances required by the laws.

10 We have also shown our improved car provided with the usual hand-operated brake staff 42 provided with the hand wheel 43 for operating the brakes by hand during the time the car is switching in the yard, or at any other time when necessary. The end of the car is also shown provided with the standard dead wood or buffer plate 44, and 15 standard couplers 45, thus fitting the car for general use.

20 We prefer employing the side and floor sections, previously described and as shown in Fig. 1, because of the great amount of longitudinal bracing afforded thereby; the side wall sections and floor sections, however, may be modified as shown in Fig. 4, as such modified form will give ample strength for general car use.

25 In the exemplification shown in Fig. 4, the side plates 46 are similar in construction to the end plates 20 of the car illustrated in Fig. 1, namely the side plates in Fig. 4 are shown of rectangular construction with their sides flanged outwardly and secured together in a similar manner to that previously described and as shown in Fig. 1.

30 In the illustration, Fig. 4, the floor-sections are also preferably of rectangular construction or form and have the flanges or sides presented upwardly and preferably riveted together in a manner similar to that previously described.

35 In this construction we also show the floor-sections provided with transversely extending nailing strips 48 on which the longitudinally extending flooring 49 may be secured in any approved manner.

40 The roof-construction and the side door 45 are shown similar to that previously described; the side door 33 in Fig. 4 being shown in closed position. We also show the end of the car provided with an end door 50 which is similar in both Figs. 1 and 4.

50 In order to convert our box-car into a refrigerator car we show the necessary lining in Fig. 5; the interior construction of our improved car being such that this lining may be readily put into place. As disclosed in Fig. 5, the end of the car is shown lined with the insulating walls 51, 52 and 53; walls 51 and 52 being of any approved insulating material, while wall 53 comprises the usual inner wooden wall.

55 The roof of the car is provided with the usual approved construction of hatchway 54 through which the necessary ice for refrigeration may be supplied to the ice-box built in the end of the car.

60 The ice-box, as disclosed in Fig. 5, consists

of the necessary grating 55 arranged along opposite sides of the ice compartment, the rack 56 on which the ice rests, the separating wall 57 and the flooring or covering 58. The entire ice compartment or box is provided with the necessary insulation at all sides and top; the top being provided with the cross-ties or carlines 59 to which is attached the layers of insulation 60 and 61 over which is laid the ceiling 62.

70 The inner side walls of the car are shown provided with suitable spaced side posts 63 to which are secured in any approved manner the insulating walls 64 and 65, all of which are covered by the inside wooden wall 66; the insulating walls 64 being shown spaced from the outer metallic section by the spacing-strips 67.

75 The floor of the car, as disclosed in Fig. 5, is shown provided with the metallic floor-sections 16, previously described, and is shown provided with cross-rails or nailing strips 68, similar to that shown in Fig. 4, and designated as 48. Secured to and intermediate of the nailing strips 68, we provide 80 the insulating wall 69, more clearly shown in Fig. 6, over which is placed the insulating wall 70 which is preferably secured on top of the nailing strips 68, as shown in Fig. 6. On top of the insulating wall 70, 85 the wooden floor 71 is laid, thus providing a thoroughly insulated car adapted for refrigerator purposes.

90 By employing the all steel floor, side and roof sections or construction, a very tight and rigid car is provided, very economical in construction and very desirable for refrigerator purposes.

95 In the construction shown in Fig. 5, we also employ the standard center sills 25, 25 and side sills 26, 26, similar in construction to those disclosed in Fig. 1.

100 In Fig. 7, we show a modified form of the end wall of the car wherein the end wall is composed of a series of steel sections 72, 110 having their flanges presented outwardly and preferably secured together with the intervening T-iron 21 disclosed in Fig. 3, while the corners are provided with the Z-bars 23, as in the previously described construction.

105 In situations where it may be found necessary to supply method or means for properly securing or blocking merchandise within the entire or certain portions of the car, the 110 method or construction disclosed in Figs. 8 and 9 may be employed. In Figs. 8 and 9, we show the side wall sections provided with recesses or grooves 73 arranged transversely of the respective sections so as to extend longitudinally of the car; these recesses or grooves 73 being shown provided with wooden filling-strips 74. The wooden filling strips 74, as shown secured in place by a piece of sheet metal 75 which may be secured to the 115

side plate or section constituting the side wall of the car in any suitable manner such as bolts or rivets.

Instead of employing the method illustrated in Figs. 8 and 9 as just described, another form of mechanism for securing merchandise may be employed, as, for example, the construction illustrated in Figs. 10 to 13, inclusive. The method illustrated in Fig. 10 comprises a pocket or socket pressed in the steel side wall sections and in the steel floor sections or plates of the car. The sockets or pockets 76 are provided with suitable staples as at 77 to which the ring 78 is secured. With this construction the merchandise may be blocked or maintained in any section or portion of the car by means of wire, rope or chain being secured to the rings of different pockets so that the space in the car containing the merchandise may be roped off as it were. The construction shown in Figs. 12 and 13 is substantially identical with that shown in Figs. 10 and 11, except that the ring 78 is omitted and a larger staple 79 is provided.

It is evident from the foregoing description and from the drawings that our improved construction may be easily adapted for any kind of house car service, as, for example, a furniture, automobile, refrigerator, express or box-car; the entire car and underframe being composed of steel, so formed and secured together that a very rigid construction is provided.

35 The reinforcing members 21, shown in Fig. 3, as arranged between the end sections, and the members 36, see Fig. 2, as arranged between the roof and side sections, not only tend to brace the respective portions of the 40 car, but also form weather-proof connections or joints; these members in their preferred form being made so as to provide portions which will overlap the adjacent ends or sides of the sections to which they 45 are secured.

We have shown and described what we believe to be the best forms of our invention. These constructions, however, may be varied in certain details without, however, departing from the spirit of our invention.

50 What we claim is:—

1. A car of the class described, having walls composed of sheet metal sections disposed vertically, the longitudinal sides and 55 upper ends of the sections being flanged outwardly, with the flanges of adjacent sections secured together, vertically disposed Z-bars arranged at the corners of the car with one leg of each bar arranged parallel with 60 the flange of the side wall section and secured thereto, while the intermediate portion of the bar is arranged parallel with the flange of the end wall section and secured thereto so as to have the other leg of the Z-bar overlap the flange of the end wall sec-

tion, the flanges of the end wall sections being secured together with intervening T-bars so as to have the head of the T-bars on the outside and overlapping the adjacent flanges, and Z-bars arranged at the upper 70 ends of the walls, with the intermediate portion of the bars extending parallel with and secured to the flanges at the upper ends of the sections so as to have one leg of the Z-bar depend and overlap the flange at the 75 upper end of the wall sections.

2. A car of the class described, having walls composed of sheet metal sections disposed vertically, the longitudinal sides and upper ends of the sections being flanged and 80 disposed outwardly with the flanges of adjacent sections secured together, vertically disposed Z-bars arranged at the corners of the car so that one leg of each bar is parallel with the flange of the side wall section and 85 secured thereto while the intermediate portion of the bar is arranged parallel with the flange of the end wall section and secured thereto, while the other leg of the Z-bar overlaps the flange of the end wall section, 90 the flanges of the end wall sections being secured together with intervening T-bars the heads whereof are arranged on the outside and overlapping the adjacent flanges, Z-bars arranged at the upper ends of the walls so as 95 to have the intermediate portion of the bars parallel with and secured to the flanges of the upper ends of the sections while one leg of the Z-bar depends and overlaps the flange at the upper end of the wall sections, the 100 inner surface of the wall sections being provided with recesses having means whereby merchandise may be secured in place.

3. A car having walls composed of sheet metal sections disposed vertically, the sections being composed of triangulated plates whose longitudinal sides incline in opposite directions, the longitudinal sides and upper ends of the respective sections being flanged and disposed outwardly, the side and end 105 walls being secured together by means of vertically disposed bars having longitudinal sides extending parallel with the flanged sides of the side and end wall sections, Z-bars arranged transversely of the upper 110 ends of the wall sections, with the intermediate portions of the bars arranged parallel with and secured to the flanges at the upper ends of the sections, while a portion of the Z-bars overlap the flanges at the upper ends 115 of the sections.

4. A car having walls composed of sheet metal sections disposed vertically, with the longitudinal sides and upper ends of the sections flanged and disposed outwardly, the 120 side and end walls being secured together by means of vertically disposed bars having longitudinal sides extending parallel with the flanged sides of the side and end wall sections, Z-bars arranged transversely of the 125 130

upper ends of the wall-sections with the intermediate portions of the bars arranged parallel with and secured to the flanges at the upper ends of said wall-sections so as to have one leg of the Z-bar overlap the flanges at the upper ends of said sections, the inner surfaces of the wall-sections being provided with recesses having means whereby merchandise may be secured thereto.

10 5. A car having walls composed of sheet metal sections disposed vertically and composed of triangulated plates whose longitudinal sides incline in opposite directions, the longitudinal sides and upper ends being flanged and disposed outwardly, the side and end walls being secured together by means of vertically disposed bars having longitudinal sides extending parallel with the flanged sides of the side and end wall sections, Z-bars arranged transversely of the upper ends of the wall-sections with the intermediate portion of the bars extending parallel with and secured to the flanges at the upper ends of said sections, while a portion of the Z-bars 15 depends and overlaps said flanges, the inner surfaces of the wall-sections being recessed and provided with means in said recesses for securing merchandise thereto.

6. A car having walls composed of sheet metal sections disposed vertically, the longitudinal sides and upper ends being flanged and disposed outwardly, the side and end walls being secured together by means of vertically disposed bars arranged intermediate of the flanges with a portion of the bars adapted to overlap the flanges on the wall exterior, Z-bars arranged transversely of the upper ends of said sections, with the intermediate portion of the bars arranged parallel with and secured to the flanges at the upper ends of the sections so as to provide a depending portion overlapping said flanges, the inner surfaces of the wall-sections being provided with transversely extending recesses provided with filling strips.

45 7. A car of the class described having walls composed of sheet metal sections dis-

posed vertically, the sections being formed of triangulated plates the longitudinal sides whereof incline in opposite directions, said sides and upper ends being flanged and disposed outwardly, the side and end walls being secured together by means of vertically disposed bars having longitudinal sides extending parallel with the flanged sides of the side and end wall-sections, Z-bars arranged transversely of the upper ends of the sections with the intermediate portion of the Z-bars arranged parallel with and secured to the flanges at the upper ends of the sections so as to have a portion of the Z-bars depend and overlap said flanges, the inner surfaces of the wall-sections being provided with transversely disposed recesses having filling strips.

8. A car of the class described, having walls composed of sheet metal sections disposed vertically with the longitudinal sides and upper ends flanged and disposed outwardly, the flanges of adjacent sections being secured together so as to provide reinforcing ribs on the car exterior arranged perpendicular to the bottom thereof, with the inner surfaces of the wall-sections being provided with recesses having means where-

by merchandise may be secured thereto.

9. A car of the class described, whose walls are composed of sheet metal sections disposed vertically and having their longitudinal sides and upper ends flanged outwardly with the flanges of adjacent sections secured together so as to provide reinforcing ribs on the car exterior disposed perpendicular to the car bottom, the inner surfaces of the wall-sections being provided with transversely disposed recesses, and filling strips arranged in said recesses extending lengthwise of the car sides and ends.
